MAGNETIC TAPE TRANSPORT

Glenn A. Smith, Redwood City, and Marvin A. Southcott,
San Francisco, Calif., assignors to Ampex Corporation,
Redwood City, Calif., a corporation of California

Filed June 27, 1963, Ser. No. 75,551

Term of patent 14 years

(Cl. D26—5)

FIG. 1

Des. 198,083

PAGE 2

FIG. 2

FIG. 3

FIG-4

FIGURE 1 is a front and side perspective of a magnetic tape transport showing our new design;

FIGURE 2 is a front elevation view;

FIGURE 3 is a side elevation view, the opposite side being substantially a mirror image thereof; and

FIGURE 4 is a rear elevation view thereof.

We claim:

The ornamental design for a magnetic tape transport, substantially as shown and described.
